UNITED STATES PATENT OFFICE

2,611,447

DIRT TRAY FOR AIR FILTERS

Charles R. Taylor, Scott City, Kans.

Application August 6, 1947, Serial No. 766,567

6 Claims. (Cl. 183—15)

1

My present invention is directed to an improvement for air cleaner devices, and more particularly, is directed to a device for facilitating removal of dirt which collects in air cleaners. This device is designed to be used with air cleaners now on the market and also in conjunction with other devices wherein dirt is collected and must be removed periodically.

In air cleaners now on the market an oil cup is provided which contains a volume of oil through which the air must pass before entry into the exhaust passage of the cleaner. As the air passes through the oil, particles of dirt are taken from the air and with time precipitate to the bottom of the oil cup. In most devices now on the market, this oil cup is removable and the dirt emptied periodically. It has been the experience of the applicant as well as others that where these fine particles of dirt are collected in the oil and permitted to precipitate for any period of time, the particles form a solid layer in the bottom of this oil cup which makes removal of it from the bottom of the oil cup very difficult, due to its packed condition and its inaccessible position. Therefore, to eliminate this difficulty, it is an object of this invention to provide a removable tray adapted to be seated in the bottom of the oil cup on which the dirt may collect.

It is a further object of the invention to provide a dirt tray having means which enable the operator to remove the dirt without the necessity of working below the level of the oil in the cup.

It is a further object of the invention to provide a dirt tray which is provided with means for loosening a compressed layer of dirt with facility.

It is a further object of the invention to provide a tray which is designed to remove particles which adhere to the sides of the oil cup as well as the dirt which collects on the tray floor.

It is a further object of the invention to provide a device which is adapted to be installed in air cleaners now on the market without change of design or installation of additional parts.

These and other objects will be obvious upon reading of the following description and reference to the accompanying drawing wherein:

Figure 1 is an elevational view of an air filter with the wall of the air cleaner broken away to disclose the dirt tray;

Figure 2 is a sectional view of the air filter with the dirt tray installed therein, taken along the line 2—2 in Figure 1;

Figure 3 is a front view of a finger for aiding in the removal of collected dirt in the filter, taken along the line 3—3 in Figure 2.

2

In Figure 1 I have shown one type of air cleaner 2, comprising a housing 4 and an oil cup 6, the latter adapted to be secured to housing 4 by a friction fit, as shown at 8, wherein a lip portion 10 is formed around the periphery of oil cup 6 and adapted to fit over the bottom of housing 4. In this type of air cleaner, apertures or inlets 12 in the side walls 5 of housing 4 are provided to permit air to be drawn into the air cleaner 2. An inside housing 14 is provided and divides housing 4 into two passages 16 and 18, these passages 16 and 18 permitting air to travel in different directions. In passages 16 and 18 material such as steel wool 20 is provided to remove foreign particles in the air before passage of the air through exhaust outlet 22. A similar construction is found in oil cup 6 wherein an inner housing 24 is provided as an extension of inner housing 14 of housing 4. Apertures 26 are provided in the walls of housing 24 to permit passage of the air from the outer passage 28 of oil cup 6 into the passage 30 of housing 24. A volume of oil, shown generally at 32, is added to the oil cup 6 so as to cover at least a portion of the apertures 26 heretofore referred to. By this arrangement, passage of air through apertures 26 into passage 30 causes the oil to be bubbled and the foam formed thereby is carried up into the steel wool or other material 20 in passage 18, thereby increasing the efficiency of the steel wool 20 in passage 18 in removing the particles in the air carried therethrough.

With continued passage of air through the cleaner 2, heretofore described, a significant amount of dirt and other particles carried in the air is deposited on the bottom of the oil cup 6 at the bottom of passages 28 and 30. In addition, a significant amount of these impurities is removed by the oil-covered steel wool or other material 20 provided in passage 18. These particles, collected on the oil-covered material 20, with continued use of the filter, are washed by the foaming oil off of the steel wool or other material 20, and find their way to the bottom of the oil cup 6, as heretofore described. Since these particles are necessarily of a fine nature, in that they are carried in the air, upon reaching the bottom of the oil cup 6 they become a solid layer, and are very difficult to remove.

To accomplish their removal, the applicant has provided dirt trays 34 and 36 which have floor portions 38 and 40, respectively, which conform to the contour of the bottom of the oil cup 6 and handle portions 42 and 44, respectively, to facilitate removal of the floor portions 38 and 40.

These trays are formed with upturned marginal portions or lips 46 and 48, respectively, which serve to remove dirt which collects on the inner walls of oil cup 6 and the inner walls of housing 24. While I have shown in Figure 1 the two trays each having its own handle, in some forms of air cleaners it would be possible to connect these handles to permit removal of both trays simultaneously by the use of these handles.

After removal of these trays, it has been found by experience that particles removed from the air by the filter and deposited on these trays are so tightly packed as to make difficult the removal of the particles from the trays. In order to facilitate the removal of these particles from the trays 34 and 36 after their removal from oil cup 6, I provide fingers or spring arms 50 and 52, and 54 and 56 for trays 34 and 36, respectively. Since all of these fingers operate in a similar fashion, reference to only one of them will suffice for purposes of description. Finger or spring arm 50 is comprised of a strip of sheet metal or the like having an arcuate configuration to conform substantially with the radius of the oil cup 6. Adjacent one end 55, it is secured to the tray portion 38 by means of rivets 58, its other end portion 60 being upturned relative to the tray portion 38 to provide a tab which will protrude above dirt that is collected on the tray and thereby permit the operator to grip this upturned portion 60. Since the spring arm 50 is anchored only at end 55, the operator is able to urge spring arm 50 upwardly relative to the tray portion 38, thereby loosening the tightly packed mass of particles. The tray is then shaken, and the loosened mass 35 emptied from the tray floor 38.

It is apparent that many variations of this invention may be made without departing from the spirit and scope thereof, and therefore I do not intend to be limited except as I have indicated in the appended claims.

I claim:

1. In an air filter structure having a cup for collecting filtered particles, a removable tray comprising a floor portion, handle means, said handle means extending from said floor portion to facilitate removal of said tray, and spring means mounted on said floor portion and adapted to be flexed relative to said floor portion to facilitate removal of particles from said floor portion.
2. In an air filter structure having a cup for collecting filtered particles, a removable tray comprising a floor portion and spring means mounted on said floor portion and adapted to be flexed relative to said floor portion to facilitate removal of particles from said floor portion.
3. In an air filter structure having a cup for

collecting filtered particles, a removable tray comprising a floor portion, said floor portion being shaped to conform with the shape of the bottom of the cup, and spring means mounted on said floor portion and adapted to have portions thereof flexed relative to said floor portion to facilitate removal of particles from said floor portion.

4. In an air filter structure having a cup for collecting filtered particles, a removable tray comprising a floor portion, and a piece of flexible material, one end of said piece of flexible material being attached to said floor portion, the other end of said piece of flexible material being turned upwardly away from said floor portion, said other end being adapted to be grasped to flex said piece of flexible material relative to said floor portion to facilitate removal of particles from said floor portion.

5. In an air filter structure having a cup for collecting filtered particles, a circularly shaped and removable tray comprising a floor portion, and a piece of flexible material curved to conform generally with the circular shape of said floor portion, one end of said piece being attached to said floor portion, the other end of said piece being turned upwardly away from said floor portion whereby to form a gripping means to facilitate flexing of said piece to aid in removal of particles from said floor portion.

6. In an air filter structure having a cup for collecting filtered particles, a circularly shaped and removable tray comprising a floor portion, handle means attached to said floor portion, and a piece of flexible material curved to conform generally with the circular shape of said floor portion, one end of said piece being attached to said floor portion, the other end of said piece being turned upwardly away from said floor portion whereby to form a gripping means to facilitate flexing of said piece to aid in removal of particles from said floor portion.
